UNITED STATES PATENT OFFICE.

HUBERT CHIPPENDALE SMITH, OF BIRMINGHAM, ENGLAND.

GAS-BURNER.

1,356,793.

Specification of Letters Patent. Patented Oct. 26, 1920.

Application filed March 16, 1920. Serial No. 366,260.

To all whom it may concern:

Be it known that I, HUBERT CHIPPENDALE SMITH, a subject of the King of Great Britain and Ireland, residing at 61 Coppley Hill, Erdington, in the city of Birmingham, England, have invented certain new and useful Improvements Relating to Gas Burners, of which the following is a specification.

10 This invention relates to gas burners, particularly of the incandescent type, and has for its object to provide simple and convenient means for the adjustment or regulation of the gas jet or jets to suit varying 15 conditions and requirements.

In the accompanying sheet of explanatory drawings:—

Figure 1 is a part sectional elevation of an incandescent gas burner nipple fitted 20 with an adjuster in accordance with this invention, and Fig. 2 is a plan of the same.

In the application of the invention as shown to the nipple of an incandescent gas burner, the jet adjuster or regulator is made 25 from a phosphor bronze or other wire having one end flattened to form a sliding or oscillatory plate or valve *a* to pass over the small gas orifice *b* or orifices formed in the outlet end of the gas nipple *c* or its equivalent. The said wire is bent at right angles 30 to form a stem *d* which is inserted in an aperture drilled longitudinally through the nipple, parallel with the gas way or conduit *e* but having no communication therewith. The wire is also bent at right angles 35 to form a lever *f* and its outer end is coiled around or otherwise attached to a button or finger grip *g*; or such end of the wire may itself be made to serve as a finger grip.

40 At the end of the said longitudinal aperture adjacent to the lever *f* a recess *h* is formed in the nipple with an open side such as will provide an abutment at one side to limit the opening movement of the lever *f*.

45 The said recess serves also to prevent projection of the adjuster beyond the adjacent end face of the nipple such as would obstruct the attachment or screwing of the nipple on to the gas supply fitting in the 50 ordinary manner.

To prevent lateral deflection of the jet when the sliding plate or valve such as aforesaid is moved across the same, the nipple is stepped or recessed adjacent to the valve as shown so that the nipple extends 55 on one side of the valve to or slightly beyond the outer face of the valve. The adapter may be otherwise modified in its details and in the complete device to meet varying services or requirements. 60

In the position shown in the drawings the valve is in the closed position, or the position for producing a minimum flow of gas through the nipple. In this position one end of the operative edge of the valve abuts 65 against the shoulder *i* formed by the stepped portion of the nipple. The said edge of the valve is made to an eccentric curved form, so that movement of the valve lever in the direction of the arrow (Fig. 2) causes the 70 nipple aperture to be progressively opened. At the limit of movement the nipple aperture is fully open.

Having thus described my invention what I claim as new and desire to secure by Letters Patent is:—

In a gas burner regulator, the combination comprising a nipple having an axial gas passage therein, a shoulder on the outer end of the nipple, a rotatable stem passing 80 through an aperture in the nipple parallel with the axis of the nipple, a valve formed integrally with the stem by flattening and bending over one end of the stem, the said valve being arranged to move over the outer 85 end of the nipple and formed with an eccentric curved edge by which the gas outlet can be varied, a finger piece formed integrally with the stem by bending over the other end of the stem, and an abutment for the finger piece formed by a recess in the nipple, movement of the valve being limited in one direction by contact of the finger piece with the said abutment, and in the other direction by contact of the eccentric edge of the 90 valve with the said shoulder, substantially as described.

In testimony whereof I have signed my name to this specification.

HUBERT CHIPPENDALE SMITH.
